UNITED STATES PATENT OFFICE.

OSCAR HAMMERSTEIN, OF NEW YORK, N. Y., ASSIGNOR TO THE UNIVERSAL CIGAR ROLLING MACHINE COMPANY, OF JERSEY CITY, NEW JERSEY.

CIGAR-ROLLING MACHINE.

SPECIFICATION forming part of Letters Patent No. 395,227, dated December 25, 1888.

Application filed August 17, 1888. Serial No. 283,014. (No model.)

To all whom it may concern:

Be it known that I, OSCAR HAMMERSTEIN, a resident of the city, county, and State of New York, have invented an Improved Cigar-Rolling Machine, of which the following is a specification.

This invention relates to cigar-rolling machines, or machines by which the wrapper of a cigar is rolled around the bunch; and the invention relates more particularly to that class of cigar-rolling machines that is represented in United States Letters Patent No. 363,065, dated May 17, 1887.

The object of this invention is to provide means to apply gum or paste to the tip of a cigar while the wrapper is being rolled upon said cigar; also, to provide improved means for holding the wrapper upon the butt-end of a cigar while said wrapper is being rolled upon a cigar.

The invention consists in the details of improvement and the combinations of parts, that will be more fully hereinafter set forth.

Reference is to be had to the accompanying drawings, forming part of this specification, in which—

Figure 1 is a plan view, partly broken, of a cigar-rolling machine containing my improvements. Fig. 2 is an enlarged detail plan view of a portion thereof, showing the point-receiving thimble and part of the gum-chamber. Fig. 3 is a vertical cross-section on the line *c c*, Fig. 1. Fig. 4 is a vertical cross-section on the line *k k*, Fig. 1. Fig. 5 is a sectional detail view on the line *k' k'* of Fig. 1, and Fig. 6 is an enlarged detail of the flexible finger *R*.

In the accompanying drawings, the letter *A* represents the frame; *B*, the curved plate or table, on which the wrapper is to be placed; *D*, the roller under the curl *b* of said table; *E*, the thimble for forming the point of the cigar; and *F G*, the rollers, which, being parallel to the roller *D*, serve to roll the cigar.

H is the pivoted frame in which the top roller, *F*, is hung, whereby said roller may be swung outward from the rollers *D G*.

a is the latch carried by the frame *H* for holding said frame in the locked position. The shafts of the rollers *D F G* carry pinions 50 that gear with a toothed wheel, *d*, carried by a shaft, *e*, that is suitably journaled in bear-

ings in the frame *A*. The shaft *e* carries a crank, *f*, or other handle, whereby said shaft may be turned to drive the rollers *D F G*. The shaft *e* has a slight longitudinal movement in its bearings, for the purpose herein-after shown.

g is the stationary and *h* is the movable part of the point-receiving thimble *E*.

The above-described parts are all old and shown, in the above-mentioned patent. I therefore refer to said patent for a more full and detailed description of said parts and their operation.

I is a chamber or receptacle for receiving 65 gum, paste, or the like, to be applied to the point of the cigar, which chamber is suitably carried by the frame *A*, and preferably extends parallel with the rollers *D F G*, as shown in Fig. 1. The chamber *I* is preferably in 70 substantially the form of a tube, which has an opening, *i*, in the top for the admission of paste and the like. This opening *i* may be kept closed by a lid, *j*, placed over the same, which lid may be held in place by a screw-clamp, *l*, that engages ledges *m* on the chamber *I*, as shown in Fig. 4; but the opening *i* in the chamber *I* may be kept closed in any other suitable manner.

At one end the paste-chamber *I* communicates, preferably through a small tube, *n*, with an aperture or passage-way, *o*, in the stationary part *g* of the point-receiving thimble *E*, as clearly shown in Fig. 3. The tube *n* is carried by a cap, *n'*, that is fitted on and covers 85 one end of the chamber *I*. (See Figs. 2 and 3.) The inner end of this aperture or passage-way *o* should come about in line with the tip or point of a cigar when said tip is in the thimble *E*, so that paste or the like that passes 90 through the passage-way *o* may pass to the tip of the cigar. The paste or the like from the chamber *I* is to be forced from said chamber through the tube *n* and passage-way *o* in small quantities, or as needed by the tips of 95 the cigars, and may be forced through said passage-way to the tips of the cigars in any desired manner; but I prefer the following construction, as being simple and effective and as giving the requisite amount of paste 100 to each cigar-tip.

J is a piston or sliding head that is placed

within the chamber or receptacle I, and that preferably closely fits the interior of said chamber, but has free movement therein.

As shown in Fig. 4, the upper side of the 5 piston J is cut away slightly or flattened, so as to pass along the flat plate j. This construction also prevents the piston turning in the chamber when being operated; but it is evident that the chamber I and the piston J 10 may be of any other shape than that shown in the drawings. To the piston J is secured a screw-rod or the like, L, that projects from one end of the chamber I. (See Fig. 1.) The screw-rod L, outside of the chamber I, passes 15 through a sleeve, p, that has internal screw-threads to engage the threads on the rod L. To the sleeve p is secured a ratchet or toothed wheel, q, which is adapted to be engaged and actuated by a dog, r, that is carried by a 20 crank, s, projecting from a rock-shaft, M, suitably journaled in bearings in the frame A. As the shaft M is rocked in its bearings, the dog r will be forced to turn the wheel q the distance of one or more teeth, thereby also 25 turning the sleeve p and moving the rod L and piston J forward a slight distance. The shaft M carries a crank, N, that is adapted to be engaged by a pin, t, on a wheel, u, carried by the shaft e.

30 My improved finger for holding the wrapper upon the end of the cigar is constructed and operated as follows: O is a short shaft that is journaled so as to have longitudinal and rotary movement in a small frame, P, that is 35 carried by the shaft F² of the roller F, and by a rod, v, in the frame II. (See Fig. 1.) The frame P is adapted to have lateral movement along the rod v and shaft F², and may be retained in the desired position by a set-screw, 40 a², carried by said frame and adapted to bear upon the rod v.

R is a finger adapted to hold the wrapper of a cigar against said cigar. Said finger is carried at one end of the shaft O, and is connected to said shaft by a spiral spring, S. (See Fig. 1.) By this means the finger R is 45 adapted to conform to the shape or size of a cigar end while holding the wrapper against said cigar. At the same time it is securely 50 carried by the shaft O and will turn with said shaft.

As shown in Fig. 1, the finger R is adapted to be passed between the rollers D F G. The shaft O carries a pinion, b², that gears with a 55 pinion, d², on the shaft F², which pinion is adapted to be turned by the shaft F². The pinion b² limits the longitudinal movement of the shaft O in its frame P by coming in contact with the sides of said frame. The lateral 60 movement of the frame P may be limited by suitable means or by a stud, e², carried by the shaft F², which stud passes into a slot in the pinion d², whereby said pinion will be turned with said shaft.

65 My improvements operate as follows: The frame II, carrying the roller F, is thrown back and a cigar-bunch is placed upon the rollers

D G, with its point in the thimble E contiguous to the end of the passage-way o. The corner of a wrapper is then placed against 70 the larger end of the cigar and the frame swung down, so as to bring the finger R against the wrapper to hold said wrapper upon the cigar, while the roller F contacts the cigar. The operator now moves the shaft e outward, 75 so as to carry the pin t on the wheel u out of line with the crank N. The cigar is now rolled in the usual way by turning the crank f. When the wrapper has been wound around 80 the cigar, and when it is about wound around 85 the point of the cigar, the shaft e is pushed inward, whereby the pin t is brought in line with the crank N. As the shaft e now continues to rotate, the movable part h of the thimble E will be reciprocated, as shown in the before-mentioned patent, while the pin t will come in contact with the crank N and rock the shaft M, thereby causing the dog r to turn the wheel q and sleeve p a slight distance—say the distance of one or two teeth. 90 As the sleeve p is thus turned, the rod L will be caused to advance slightly, thereby pushing the piston J against the paste or the like contained in the chamber I. As the piston is thus moved forward, it will force a small 95 amount of paste or the like through the tube n and passage-way o and against the tip of the cigar. As the cigar continues to rotate, the paste will be distributed upon the cigar tip and wrapper at the tip evenly and uniformly, so that when the cigar is removed 100 from the rollers the wrapper will have had paste applied to it, thereby dispensing with the necessity of an operator applying paste by hand after the cigar was rolled, as has hereto- 105 fore been done.

It will be noticed in the drawings that the thimble E is separate and independent from the means for holding and rolling the cigar-bunch. If, now, any excess of paste were 110 forced into the thimble, it would not cover the body of the cigar, but would pass out of the thimble and drop below, thereby pasting the point only of the cigar.

Having now described my invention, what I 115 claim is—

1. In a cigar-rolling machine, the combination, with means, as described, for rolling a cigar, of a shaft, O, finger R, and spring S, interposed between the end of said finger and the end of said shaft, connecting said finger to said shaft, substantially as described.

2. In a cigar-rolling machine, the rollers for rolling a cigar, combined with shaft O, having pinion b², finger R, and spring S, connecting the finger R to the shaft O, and with the pinion d², meshing with the pinion b², shaft F², and the independent frame P, supporting the shaft O, whereby said shaft may have longitudinal movement, all arranged for operation substantially as described.

3. In a cigar-rolling machine, the combination, with means for rolling a cigar, of the rotatable shaft O, the rigid finger R, and the

flexible connection between said finger and shaft, whereby the former is rotated by the latter, but can conform to the size and shape of the cigar, substantially as described.

5 4. In a cigar-rolling machine, the combination of means, substantially as described, for rolling a cigar and a point-receiving thimble, the stationary part of said thimble having a passage-way, *o*, with a paste-chamber, *I*, hav-

ing a cap, *n*¹, the tube *n*, carried by said cap, ¹⁰ and with means, substantially as described, for pressing paste from the chamber *I* to the thimble *E*, substantially as specified.

OSCAR HAMMERSTEIN.
